UNITED STATES PATENT OFFICE.

JOHN F. McCANNA, OF CHICAGO, ILLINOIS, ASSIGNOR TO IMPERIAL BRASS MANUFACTURING COMPANY, OF CHICAGO, ILLINOIS, A CORPORATION OF ILLINOIS.

SIGHT-FEED LUBRICATOR.

1,095,654.

Specification of Letters Patent.

Patented May 5, 1914.

Application filed April 20, 1912. Serial No. 692,093.

To all whom it may concern:

Be it known that I, JOHN F. McCANNA, a citizen of the United States, and a resident of Chicago, in the county of Cook and State of Illinois, have invented certain new and useful Improvements in Sight-Feed Lubricators, of which the following is a full, clear, and exact specification.

My invention is concerned with sight-feed lubricators for oiling the bearings of engines, etc., and is designed to produce a simple but efficient construction in which a single pump for each bearing to be lubricated will not only pump the oil to the bearing, but will also serve to operate a constant sight feed showing the amount of oil that is being pumped to the bearing. In most devices of this character heretofore used, two pumps have been necessary to effect this result; but with my invention a single pump, in combination with a supply well and a sight-feed pipe leading into the well from the reservoir and terminating adjacent a transparent portion of the well, serves to produce the same results as the two pumps heretofore used. In my invention, there is the additional certainty that the same amount of oil is being pumped to the bearing as is indicated by the sight feed, as the same pump moves the oil into the supply well to furnish the sight feed, as well as to force it from the well to lubricate the bearing.

To illustrate my invention, I annex hereunto a sheet of drawings, in which the same reference characters are used to designate identical parts in all the figures, of which,

Figure 1 is a vertical section through the pump barrel and well; while Fig. 2 is a similar section through the pump barrel at right angles to the section shown in Fig. 1.

In carrying out my invention, I provide a reservoir 5, the body of which may be of any desired construction, and which I have shown as consisting of a casting provided with the necessary internal flanges, projections, etc., to accommodate the various operating elements and connections employed therewith. The cover 6 is secured thereon in any suitable manner, as by the screws 7, and it will be understood that the cover must not be air-tight: that is to say, the oil in the reservoir must have atmospheric pressure on its upper surface, and to insure this I provide one or more apertures 8 in the cover

for this purpose. The cover 6 is likewise preferably a casting, and has the central cylinder or barrel 9 which is connected by the passage 10 with the valve cylinder 11, on one side, and is similarly connected by the passage 12 with the well cylinder 13. The check valve 14, which preferably takes the form of a heavy steel ball, is located at the end of the passage 12 so as to permit of the oil being drawn from the well 13 into the barrel 9, but so as to prevent its being forced in the opposite direction by the piston 15 reciprocating in the barrel, a wire 16 extending across the barrel above the valve 14 preventing possible displacement of the latter. The valve cylinder 11 is preferably provided with a pair of valve seats to accommodate the two check valves 17 and 18 seated thereon, which are preferably of different sizes of steel balls, and which serve to permit of the forcing of the oil from the barrel 9 through the pipe 19 to the point of discharge, but which prevent the possible backward movement of the oil when the piston 15 is raised. This pipe 19 is connected with the valve cylinder 11 by means of the plug 20 screwed into the top of the cylinder and having a passage therethrough, and provided at its upper end with the stuffing box 21, by which a liquid-tight connection is made between the pipe 19 and the plug 20. The upper end of the pump barrel 9 is similarly provided with the customary stuffing box 22 through which the piston 15 reciprocates. A shaft 23 is journaled in suitable bearings formed in the casing, and is preferably reciprocated by any suitable means driven by the engine or machinery to be lubricated. An arm 24 secured on the shaft 23 inside of the reservoir 5 carries a pawl 25 which co-operates with the teeth of a ratchet wheel 26 loosely mounted on the shaft 23 and rigidly secured to an eccentric 27 co-operating with the yoke 28 secured on the lower end of the vertically reciprocating rod 29 extending up through the cover 6 and connected by the cross head 30 with the piston 15. By means of the stationary abutment 31 secured on the piston 15 and the adjustable abutment or nut 32 threaded thereon and having a co-operating lock nut 33, the amount of lost motion between the rod 29 and the piston 15 can be determined to regulate the rate of feed of the oil.

Coming now to the sight-feed mechanism,

which constitutes the essentially novel portion of my invention, the well cylinder 13 is provided above the cover 6 with a transparent portion which is preferably formed by using the glass cylinder 34 resting on the packing ring 35 seated on an annular surface surrounding the top of the cylinder 13. A similar packing ring 36 rests on the top of the glass cylinder 34, and a cylindrical cap 37 having cut-away portions 38 has its lower end threaded into the shallow recess into which the bottom of the glass cylinder 34 extends. An internal annular shoulder of the cap 37 co-operates with the packing ring 36, so that when the cap 37 is securely screwed in place, the well made up of the lower cylindrical portion 13 and the upper transparent portion is air-tight. A sight-feed tube 39 passes through the bottom of the well to substantially the bottom of the reservoir 5, and it is soldered or otherwise secured in the well so that no air can enter the well from the reservoir. The upper end of the tube 39 is curved, as at 40, so that the oil passing from the reservoir into the well through the tube 39 will fall, drop by drop, in front of the transparent portion of the well, so that an observer can note the rate at which the oil is falling.

80 The operation of my improved apparatus will be readily apparent, as when the pump piston is reciprocated by the mechanism described, the oil will be drawn from the bottom of the well through the passage 12 into the barrel 9, whence it will be discharged through the passage 10 into the pipe 19 leading to the part to be lubricated. As the oil is drawn from the air-tight well, the pressure of the air in the well above the level of the oil is reduced, and, as a consequence, the atmospheric pressure on the oil in the reservoir serves to force the latter up through the tube 39 and to deliver the oil, drop by drop, into the well at exactly the same rate as it is pumped therefrom by the reciprocation of the piston 15, thus giving an absolute and constant indication of the rate at which the oil is being pumped. As the oil falls from the pipe 39 into the well, it seemingly carries with it a small portion of the air in the well, so that in the course of a month or so the height of the oil in the well rises to a point so as to interfere with the operation of the sight feed.

55 To remedy this, some means must be provided for admitting air into the well sufficient to cause the level of the oil in the well to fall, and for this purpose I provide the screw 41 threaded into the top of the cap 37, and provided with the packing ring 42, so that when it is screwed up tight the well will be air-tight. When the oil in the well has risen to a point to interfere with the operation of the sight feed, the screw 41 is loosened until the air can enter the top of

the well, and the operation of the pump continues as usual, without the sight feed, however, until the contents of the well have been lowered to the desired point, after which the screw 41 is tightened up and the 70 operation of the sight feed resumed.

While I have shown and described my invention as embodied in the form which I at present consider best adapted to carry out its purposes, it will be understood that it is 75 capable of modifications, and that I do not desire to be limited in the interpretation of the following claims except as may be necessitated by the state of the prior art.

What I claim as new, and desire to secure 80 by Letters Patent of the United States, is:

1. In a sight-feed lubricator, the combination with a reservoir open to atmospheric pressure, of a cover therefor having a pump-barrel and a supply-well cylinder 85 formed therein, a valved passage connecting the bottom of the barrel and the supply-well cylinder, a valved passage leading from the barrel to the point to be lubricated, a glass cylinder adapted to form a continuation of the well above the top of the cover, a cap for the cylinder secured to the cover forming an air-tight connection between the two cylinders, a sight-feed pipe leading from the bottom of the reservoir into the well and terminating in the glass portion, a pump piston reciprocating in the barrel, and means for reciprocating the piston.

2. In a sight-feed lubricator, the combination with a reservoir open to atmospheric pressure, of a cover therefor having a pump barrel and a supply-well cylinder formed therein, a valved passage connecting the bottom of the barrel and the supply-well cylinder, a valved passage leading from the barrel to the point to be lubricated, a glass cylinder adapted to form a continuation of the well above the top of the cover, a cap for the cylinder secured to the cover forming an air-tight connection between the two cylinders, a sight-feed pipe leading from the bottom of the reservoir into the well and terminating in the glass portion, a pump piston reciprocating in the barrel, means for reciprocating the piston, and a screw in the top of the cap, for the purpose described.

3. In a sight-feed lubricator, the combination with a reservoir open to atmospheric pressure, a cover for said reservoir, an air-tight supply-well carried by the cover and having a transparent portion extending above the same, an unobstructed sight-feed pipe leading from the bottom of the reservoir into the well and terminating adjacent the transparent portion, and capable of delivering oil up to the full capacity of the pump, a pump carried by the cover drawing its supply from the well, a passage connecting the well with the pump unobstructed as to the flow therethrough of the oil from

the well to the pump and serving at all times to deliver oil to the pump up to the full capacity at which the piston is working, a check valve in said last mentioned 5 passage, means for operating the pump, and means for regulating the rate at which the pump operates to discharge the oil.

In witness whereof, I have hereunto set my hand and affixed my seal, this tenth day of April, A. D. 1912.

JOHN F. McCANNA. [L.S.]
